UNITED STATES PATENT OFFICE.

HENRY S. NUNAMAKER, OF CANTON, OHIO, ASSIGNOR TO THE V. L. NEY HAY TOOL COMPANY, OF CANTON, OHIO, A CORPORATION OF OHIO.

HAY-CARRIER.

1,346,243.

Specification of Letters Patent.

Patented July 13, 1920.

Application filed December 5, 1919. Serial No. 342,733.

To all whom it may concern:

Be it known that I, HENRY S. NUNAMAKER, a citizen of the United States, residing at Canton, in the county of Stark and 5 State of Ohio, have invented a new and useful Hay-Carrier, of which the following is a specification.

This invention relates to hay carriers and has more especial reference to cross draft 10 hay carriers or that class of carriers in which the elevating rope leads from the carrier in a direction substantially at a right angle to the track along which the carrier moves.

15 The objects of the invention are to provide a hay carrier of the character mentioned with a rope locking lever which is operated by the elevating rope and which controls the operation of a rope grip arranged to 20 lock the elevating rope at any desired elevation; and to generally improve and simplify the construction of hay carriers.

With these objects in view the invention consists in the novel construction and arrangement of parts, hereinafter described, 25 illustrated in the accompanying drawings, and particularly pointed out in the appended claims, it being understood that various changes in the form, proportions, size 30 and minor details of construction may be made within the scope of the appended claims, without departing from the spirit or sacrificing any of the advantages of the invention.

35 The invention thus set forth in general terms is illustrated in the accompanying drawings forming part hereof, in which—

Figure 1 is a perspective view of a hay carrier embodying the invention mounted 40 upon the track, the elevating rope being removed in order to illustrate the mechanism of the carrier.

Fig. 2 is a vertical sectional view through the hay carrier showing the parts in the 45 locked position.

Fig. 3 is a view similar to Fig. 2 showing the parts in the unlocked position.

Fig. 4 is a detail perspective view of the rope grip.

50 Fig. 5 is a sectional view through a barn showing the carrier in use.

A practical embodiment of the invention is disclosed in the accompanying drawings, forming a part of this specification in which 55 similar numerals of reference indicate cor-

responding parts throughout the several views.

The track 1 upon which the carrier is adapted to run may be made of any suitable or well known form and is suspended from 60 any substantial support such as the rafters of a barn. The main frame 2 of the carrier is suspended upon the track frame 3, which is provided at its ends with the rotatably traveling wheels 4 adapted to run upon the 65 track.

The main carrier frame is preferably formed of a casting as shown and comprises two spaced sides joined together at suitable points. The side members of the main 70 frame are each provided with an upwardly disposed ear 5, a bolt or pin 6 being passed through said ears and through the frames 7 of the truck frame. It will thus be seen that the carrier with its load is suspended 75 from eight traveling wheels, four being arranged at the front and four at the rear.

In the main frame at a point substantially beneath the center of the track is located the main sheave axle 8, which extends transversely from one side of the frame to the other and upon which is rotatably mounted the main sheave 9. This sheave is preferably of considerable diameter to lighten 85 the draft as much as possible and facilitate the operation of the carrier.

Pivotedly mounted upon the main sheave axle 8 is the rope locking lever 10 which is formed of two similar members spaced apart, one member being mounted upon each 90 side of the main sheave, these members being joined together at their rear and forward ends respectively by means of pins or bolts 11 and 12. The rope locking lever extends outwardly to one side of the main 95 frame and is provided with a downwardly depending portion 13 in which is carried the roller 14 mounted upon the bolt 12. A pair of spaced arms 15 are mounted one upon each side of the rope locking lever 100 and connected thereto by means of the bolt 12. A pulley 16 being mounted between the outer extremities of said arms by means of a bolt 17 or the like.

The sheave brake 18 is pivotally mounted 105 upon a suitable axis 19 located transversely through the main frame adjacent to the main sheave 9. The rope grip 20 is preferably of the form best illustrated in Fig. 4 of the drawings and is provided with the 110

bifurcated portion 21 which is pivotally mounted between the side members of the main frame upon a bolt 22. The free end of the rope grip is curved as shown at 23 and provided with a serrated grooved face 24, the rope grip being so proportioned and mounted that it will normally rest upon the rope as best illustrated in Fig. 2. The transverse bolt or pin 11 upon the rope 10 locking lever normally engages the under surface of the rope grip as shown in Fig. 2. In reeving the carrier, one end of the elevating rope 25 is connected to the transverse bar 26 of the frame either by knotting or by use of a device such as the rope clamp 27. Extending downwardly the rope passes through the lifting head or heads of the fork sling or other hay engaging device, in the present illustration sling pulleys 28 being shown. The rope then extends upward from these sling pulleys or other hay engaging device over an idler pulley 29 pivotally mounted upon a bolt 30 carried in the main frame, and passes over the main sheave and then outwardly 25 between the rollers 14 and 16 upon the rope locking lever.

From this point the elevating rope extends downwardly at an angle either to 30 the side of the barn in which the carrier is mounted and over the usual purlin pulley or downward at an angle to the floor of the barn and over the usual floor pulley, this construction of course being common 35 in all cross draft hay carriers and is well known to those acquainted with the construction and operation of cross draft hay carriers and as it forms no part of the present invention it is thought unnecessary to 40 illustrate either of these pulleys in the present application.

It will be understood that the carrier is arranged to be moved longitudinally upon the track in the usual manner by means of 45 the ordinary shift rope or conveyer rope, which arrangement is well known to all those skilled in the art and has no relation to the present invention excepting that similar means is always provided for moving 50 the carrier upon the track.

The operation of the hay carrier embodying this invention is as follows: The parts being in the unlocked position as illustrated in Fig. 3 it will be noted that the rope locking lever is tilted forwardly upon its pivotal point, the rear end thereof being raised, holding the rope grip out of engagement 55 with the elevating rope as shown. If, as above mentioned the elevating rope leads 60 downwardly at an angle to the usual pulley on the barn floor, the rope locking lever is moved into the unlocked position as shown by grasping the elevating rope at any point above the floor and swinging the rope toward the carrier, the rope engaging the pul-

ley 14 and tilting the rope locking lever into the unlocked position. If, however, the elevating rope extends from the carrier to the purlin pulley upon the side of the barn wall as also above mentioned, it will 70 be understood that this purlin pulley is out of reach of a man upon the floor of the barn. For this purpose a trip lever 31 is pivotally mounted at any suitable point in the carrier frame such as the axis 22 of 75 the rope grip and extends inwardly to a point beneath the pin 11 upon the rope locking lever, a cord 32 is connected to the outer end of the lever 31 and extends downwardly to the barn floor. By pulling downward 80 upon the cord 32 the trip lever 31 is rocked tilting the rope locking lever and raising the rope grip. The fall of the elevating rope may then be brought down to the point of attachment of the load. When 85 the load is attached and a pull exerted upon the elevating rope the load will be raised toward the carrier, the rope passing over the main sheave preventing the rope grip from gripping the elevating rope. When the 90 load has been carried up to the carrier the weight of the load will be sufficient to hold the elevating rope taut in a straight line from the main sheave to the pulley upon the 95 purlin or floor pulley over which the other end of the rope passes, the elevating rope being held in the position shown in Fig. 2 engaging the pulley 16 and tilting the rope locking lever upward at its outer end allowing 100 the rope grip to drop into engagement with the rope as shown in said figure, the weight of the load pulling down upon the elevating rope, swinging the rope grip downwardly upon its pivotal point 22 causing the serrated surface thereon to grip the 105 rope tightly and pressing the rope against the sheave brake 18, pressing the brake in turn in tight engagement with the sheave, thus locking the sheave and the rope.

It should be noted that with the movement of the elevating rope in either direction over the main sheave the rope grip is swung upwardly or downwardly upon its pivotal point, always swinging in the opposite direction from the rotation of the 115 sheave. Thus it will be seen that the main sheave itself is locked against rotation by means of the brake 18 and the elevating rope is gripped by the rope grip preventing movement of either the sheave or the rope 120 while in this position.

The carrier will then be moved along the track in the usual manner to the place of discharge, the load being thus sustained in the position shown in Fig. 2 when the carrier has reached the place of discharge, the sling or fork carried thereby is tripped in the usual manner discharging the load of hay and the carrier moved back to the loading position, when as above described by 130

swinging the elevating rope toward the carrier the rope locking lever is moved into the position shown in Fig. 3 and the fall of the rope be again lowered to receive a new load.

5 In Fig. 5 is illustrated an application of the carrier wherein the elevating rope 25 leads to a purlin pulley 35 and then down to a floor pulley 36, a pulley 37 being mounted upon the elevating rope between the carrier 10 and the purlin pulley and provided with an operating cord 38 which hangs within reach of the operator and may be pulled down as shown in said figure to pull the operating rope downward and inward to trip the locking lever as above described. After the carrier 15 has been tripped in this manner it is customary to exert a pull upon the elevating rope to raise the carrier, the slack being thus removed from the elevating rope between the carrier and the purlin pulley raising the pulley 37 into the position shown in dotted lines, the operating cord hanging in the dotted position shown in the drawings. With 20 this construction the carrier may be used 25 with a purlin pulley without the necessity of using the trip lever 31 and cord 32.

I claim:

1. A hay carrier provided with a main sheave, a locking lever connected to said carrier, a rope grip pivoted within the carrier and resting upon the locking lever, an elevating rope connected to the carrier and passing over the sheave and forming a fall, the rope grip arranged to normally engage 35 said elevating rope and means for tilting the locking lever to swing the rope grip out of engagement with the elevating rope.

2. A hay carrier provided with a main

sheave, a locking lever pivoted upon said carrier, a rope grip pivoted within the carrier and resting upon the locking lever, an elevating rope connected to the carrier and passing over the sheave and forming a fall, the free end of the rope engaging the free 40 end of the locking lever, the rope grip arranged to normally engage the elevating rope, the locking lever arranged to be tilted by an inward pull upon the elevating rope 45 to throw the rope grip out of engagement with the elevating rope. 50

3. A hay carrier provided with a main sheave, a locking lever connected to said carrier, a rope grip pivotally mounted within the carrier and normally resting upon the locking lever, an elevating rope connected 55 to the carrier and passing over the sheave and forming a fall, a sheave brake located within the carrier and arranged to be operated by the action of the rope grip upon the elevating rope and means for tilting the 60 locking lever to release the rope grip.

4. A hay carrier provided with a main sheave, a locking lever pivoted to said carrier, a rope grip pivotally mounted within the carrier and normally resting upon the 65 locking lever, and an elevating rope connected to the carrier and passing over the sheave and forming a fall and arranged to be normally engaged by the rope grip, said elevating rope engaging the locking lever 70 and arranged to move the locking lever into the locked or unlocked positions.

In testimony that I claim the above I have hereunto subscribed my name.

HENRY S. NUNAMAKER.
